UNITED STATES PATENT OFFICE

HENRY JULES LOUN, OF BROOKLYN, NEW YORK, ASSIGNOR TO WULLSCHLEGER & CO., OF NEW YORK, N. Y.

DESIGN FOR A TEXTILE FABRIC OR THE LIKE

Application filed November 8, 1932. Serial No. 45,826. Term of patent 3½ years.

To all whom it may concern:

Be it known that I, HENRY JULES LOUN, a citizen of the German Republic, residing at No. 960 Green Avenue, in the borough of Brooklyn, city of New York, county of Kings, and State of New York, have invented a new, original, and ornamental Design for a Textile Fabric or the like, of which the following is a specification, reference being had to the accompanying drawing, forming part thereof.

The figure is a surface view of a piece of textile fabric or the like, showing the design.

The area within the dot and dash lines shows one complete unit of the design. The repeats are arranged in vertical rows and adjacent vertical rows are one half a complete unit offset so that the angle of the complete unit indicated by letter A corresponds with angle B of one of the repeats in an adjacent vertical row.

I claim:

The ornamental design for textile fabric or the like, as shown and described.

HENRY JULES LOUN.
